United States Patent Office

Des. 210,896
Patented Apr. 30, 1968

210,896

LAZY SUSAN

Edward E. Heck, Berwyn, Ill., assignor to Republic Molding Corporation, Niles, Ill., a corporation of Illinois

Filed May 15, 1967, Ser. No. 7,110

Term of patent 14 years

(Cl. D44—10)

FIG. 1

FIG. 2

FIG. 3

FIG. 5

FIG. 4

FIG. 6

FIG. 1 is a top perspective view of a lazy susan showing my new design;

FIG. 2 is a bottom perspective view;

FIG. 3 is a top plan view;

FIG. 4 is a bottom plan view;

FIG. 5 is an elevational view taken from the right of FIG. 3; and

FIG. 6 is an elevational view taken transversely with respect to the view in FIG. 5.

I claim:

The ornamental design for a lazy susan, substantially as shown.
